UNITED STATES PATENT OFFICE.

JOHN W. HOLDSWORTH, OF ST. LOUIS, MISSOURI, ASSIGNOR OF ONE-HALF
TO ROBERT DODSWORTH, OF SAME PLACE.

ALARM FOR ELEVATORS.

SPECIFICATION forming part of Letters Patent No. 381,015, dated April 10, 1888.

Application filed April 5, 1887. Serial No. 233,755. (No model.)

To all whom it may concern:

Be it known that I, JOHN W. HOLDSWORTH, of the city of St. Louis, in the State of Missouri, have invented a certain new and useful Improvement in Alarms for Elevators, of which the following is a full, clear, and exact description, reference being had to the accompanying drawings, forming part of this specification.

10 This is a device to cause a continuous ringing of a bell when the elevator is in operation. It broadly consists in securing to a moving part a frame supporting a bell, and a wheel or pulley running on a fixed object, with a device 15 by which the rotation of the wheel imparts motion to the bell-hammer. In an evident modification the bell and wheel or pulley frame are attached to a fixed object and the wheel turned by connection with the hoisting or hand cable.

20 Figure I shows the device applied to the car of an elevator. Fig. II is an enlarged side view of the device. Fig. III is a detail end view, part in section. Fig. IV shows a modification of the mechanism between the drive-wheel and the bell-hammer. Figs. V, VI, and VII are elevations, showing modifications of the means for driving the wheel or pulley. Fig. VIII is an axial section of the friction-wheel, showing its relation to the hooked rod 25 to which it imparts motion. Fig. IX is an edge view of a friction-pulley of slightly modified form. Fig. X is an elevation, showing in detail some of the parts shown in Fig. IV.

The device, with its modification, will be described in the order in which the figures occur.

1 are the upright guide-posts at the sides of the car. 2 is part of the car, and 3 the cross-bar at the top of the car.

4 is a frame connected to the cross-bar 3 by a hinge, 5, at one end.

6 is a wheel whose shaft has bearing on standards 7, fixed to the frame 4. The frame 4 inclines upwardly from the hinge, and its wheel 6 has peripheral bearing against one of the posts 1. The inclination and the weight of the frame with its appendages are such that the wheel bears with sufficient force against the post to cause the rotation of the wheel. The frame accommodates itself by change of inclination to any transverse movements in

the car to or from the post, against which the wheel bears.

8 is a flanged wheel on the shaft of the wheel 6, the flange having an inwardly-projecting tooth or stud, 9.

10 is the bell-hammer at the upper end of an arm, 11, which is hinged to the frame 4 at the lower end.

12 is a spring drawing the hammer toward the bell 14.

13 is a rod hinged to the bell arm. The rod 13 is hooked at the end 15, the hook engaging the flange 8 upon its interior. At each rotation of the wheel 6 the tooth 9 engages the hook 15 and draws the hammer away from the bell. On the release of the hook from the tooth the hammer strikes the bell, and thus, when the car is in motion, the bell continues to sound. To prevent the hammer remaining in contact with the bell after striking it, there is a stop-pin, 16, in the lug, to which the arm 11 is hinged, and the arm is notched at 17 to give place for the stop-pin. When the hammer is at rest, the shoulder at one end of the notch 17 bears against the stop-pin and holds the hammer just out of contact with the bell. (See Fig. II.) The flexibility of the arm 11 allows the momentum of the hammer to carry it into contact with the bell when the hook is released from the tooth 9.

In the modification shown in Fig. IV the shaft of the wheel 6 carries a crank, 18, whose wrist-pin 19 carries a cord or wire, 20, connected to a lever, 21, having a tilt-plate, 22, engaging the arm 11 of the hammer 10, so that at each rotation of the wheel 6 the hammer is drawn outward by the pressure of the tilt-piece against a projection, 11^a, of the arm 11, from which it escapes as the lever and arm move outward and the hammer is thrown against 90 the bell by the spring 12.

25 is a spring attached to the tilt-piece tending to hold it in the position shown, so that it will engage the projection of the arm 11 on moving outward, the spring 25 also acting to return the lever 21 to its normal position. As the lever is returning to its normal position, the tilt-piece is pressed aside and passes the projection of the hammer-arm. This device, consisting of the hammer with its pivoted 100

arm, and the actuating-lever with the tilt-piece, and the springs by which they are drawn toward the bell, is old in connection with bells and gongs, and no novelty is claimed in them, 5 and no further description is necessary.

In the modification shown in Fig. V the wheel or pulley 6^a is grooved at the periphery, and bears against the hand-cord 23, so that the bell may be sounded by the movement of the 10 hand-cord, and will continue to sound while the car is moving.

In the modification shown in Fig. VI the wheel or pulley 6^a is grooved at the periphery, and the hand-cord is given a turn around it to 15 insure its turning as the hand-cord is moved, or as the car moves. In this modification, and also in the modification shown in Fig. V, the frame 4 may be rigidly connected to the car.

In the modification shown in Fig. VII the 20 frame 4 is hinged to a fixed object, 24, and the wheel or pulley 6^a is peripherically grooved and bears against the cable 25, by which the car is raised, so that the bell is caused to sound during the movement of the car. In 25 the form shown in Fig. VII it is not essential that the frame 4 should be jointed to the object to which it is connected, as the transverse position of the cable 25 would not vary materially.

30 I claim as my invention—

1. In an elevator, the combination, with the fixed and the movable parts thereof, of a wheel affixed to one and bearing constantly against the other, so as to be rotated continuously during the movement of the elevator, a bell, a hammer for sounding the bell, and mechanism act-

uated by the wheel for imparting motion to the hammer, whereby the latter causes the bell to sound continuously during the movement of the elevator, substantially as set forth. 40

2. The combination, with an elevator-car, of the swinging frame 4, jointed at one end thereto, a wheel or pulley, 6, carried by said frame and bearing against an upright, as post 1, a bell, a hammer, and mechanism actuated by the 45 wheel 6, communicating motion to the bell-hammer, substantially as set forth.

3. The combination, with the elevator-car, of a frame hinged at one end thereto, a wheel, 6, carried by said frame and bearing against post 50 1, a bell carried by said frame, a bell-hammer, a wheel, 8, rotated by the wheel 6 and having a tooth, 9, the rod 13, engaging at one end with the bell-hammer and engaged at the other by said tooth, and the spring 12, connected to the 55 hammer for throwing it against the bell, substantially as and for the purposes set forth.

4. The combination, in an elevator-alarm, of the frame 4, hinged to the car, a wheel, 6, carried by said frame and bearing against the 60 side post, 1, the flanged wheel 8, carried by wheel 6 and having tooth 9 located upon its inner periphery, the rod 13, having hooked end 15, adapted to be engaged by the tooth 7, the bell 14, the hammer 10, arm 11, by which 65 it is carried, and the spring 12, for forcing the hammer against the bell, substantially as and for the purposes set forth.

JOHN W. HOLDSWORTH.
